Howard C. Thompson
ATTORNEY

UNITED STATES PATENT OFFICE

JOSEPH SOSS, OF BROOKLYN, NEW YORK

HINGE

Application filed September 21, 1927. Serial No. 220,924.

This invention relates to hinges and particularly to devices of this class, the separate butts of which are composed of sheet metal and fashioned to form a plurality of pintle bearings extending longitudinally of the hinge to provide an elongated hinge structure for supporting a door or other swinging member in connection with a stationary support or door frame; and the object of the invention is to provide a hinge of the class specified, one of the butts of which is fashioned from a single sheet of comparatively thin sheet metal, in such manner as to provide a plurality of cylindrical pintle bearings, spaced longitudinally of one side edge of the butt and contained within a hood portion forming what is known as a covered joint hinge wherein a plurality of cylindrical pintle bearings or knuckles are arranged longitudinally of the hood portion and recesses intermediate said bearings for receiving the pintle bearings or knuckles of the other butt of the hinge; a further object being to provide a hinge butt of the class described which is so fashioned as to produce, longitudinally of the free edge of the hood portion, a stop shoulder for limiting the movement of the separate butts one upon the other; and with these and other objects in view, the invention consists in a hinge of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a side view of a hinge made according to my invention, with part of the construction broken away and in section. Figs. 2 to 5 inclusive are sectional views, showing the successive steps in the formation of one of the butts of my improved hinge.

Fig. 6 is a section on the line 6—6 of Fig. 1.

Fig. 7 is a section on the line 7—7 of Fig. 1; and,

Fig. 8 is a sectional view, showing a modification.

In the drawing, 10 represents one of the butts of the hinge, and 11 the other butt thereof. The butt 10, in the construction shown, is formed from a single sheet of metal, the central portion of which is fashioned to form a plurality of cylindrical bearings 10^a, spaced longitudinally thereof and between which are recesses 10^b to receive the pintle bearings or knuckles of the butt 11.

The butt 11 is fashioned from a single sheet of metal, the central portion of which is cut out to form a plurality of apertures 12, spaced longitudinally of the sheet and between which are web portions 13, one web portion and one aperture being represented in Fig. 2 of the drawing. The web portions 13 are then fashioned to form substantially cylindrical members 14 as indicated in Fig. 3 of the drawing, by bringing the side parts 11^a and 11^b of the sheet together to form the shank of the butt, after which the members 14 and adjacent part of the shank are curled upon the shank of the butt as partially indicated in Fig. 4 until the parts assume the position shown in Fig. 5, in which position it will be noted that the bearings 14 which constitute the pintle bearings of the butt are contained within a hood portion 15 of a double wall thickness where the bearing members 14 are located, and of a single wall thickness intermediate said bearings at the recesses between said pintle bearings as seen at 15^a, Fig. 6 of the drawing to provide a free clearance as at 16 for the cylindrical bearings 10^a of the butt 10 of the hinge. This clearance is provided by the cut outs or apertures 12 in the sheet from which the butt 11 is formed, which apertures terminate in the inner wall member at 17 as seen in Fig. 6 of the drawing, and in the outer wall member at 18 to form a stop shoulder.

In forming the butt 11, and especially in securing the same to the pintle 19 of the hinge, which is passed through the bearings 10^a

14 and 10^a, the bearings 14 are firmly secured to the pintle by applying pressure and crimping said bearings at 20 into alignment with the free edge or stop shoulder 18 as seen in Fig. 6 of the drawing. This operation securely binds the bearings 14 onto the pintle 19, whereas the bearings 10^a are free to rotate on said pintle.

It will also be understood that the separate 10 sectional portions of the butt 11 may be secured together by riveting, welding or in any other desired manner. The shank portion thereof, in the formation of the butt, is offset as seen at 21 at right angles to said 15 shank, and then offset as seen at 22 into the plane of the shank and at right angles to the part 21, the offset 22 constituting the attaching plate portion proper of the butt. As seen in Fig. 1 of the drawing, the offset 21 20 is curved to the opposite ends of the butt in a longitudinal plane to adapt the attaching plate to the door and door frame having curved outer surfaces, such for example as the door and door frame of a motor vehicle.

25 From the foregoing, it will be seen that the distinctive feature of my invention resides in the construction of the butt 11 and in the manner of forming the pintle bearing portion of said butt from a single sheet of 30 metal, and to form of said sheet, a hood portion which encloses the hinge joint throughout the length thereof and provides between the bearings of said butt, within said hood member, recesses to receive the 35 bearing members of the other butt of the hinge. It will also be understood that the three wall thickness provided where the bearings 14 are located in the butt 11, produces a strong and durable hinge.

40 By folding the sheet material around a suitable tool in the formation of the bearings 14, I provide a knuckle which is insured against opening or spreading when subjected to stress, to a greater degree than knuckles 45 curled at the end of a sheet of metal as is the common practice, it being noted that the stress of the door or swinging member upon the stop shoulder is taken up directly by the hood portion which will prevent the opening 50 or spreading of the pintle bearings or knuckles 14 to a material degree. It will also be understood that with my improved method of constructing the hinge butt, all machining operations are eliminated, and the 55 production costs of the butt reduced to the minimum degree, and yet a strong and durable butt is produced.

It will also be understood that my hinge 60 is designed to be used as a single unit or body for hanging and supporting a door in connection with a stationary support or frame without the use of other hinge members, and to eliminate the necessity of using a plurality of independent hinges as is the common 65 practice. By means of a hinge of my im-

proved type, considerable time and labor is saved in the assemblage and mounting of a door in a frame, and the proper and accurate hanging of the door is facilitated.

In Fig. 8 of the drawing, I have shown a 70 modified method of forming the butt part 11 wherein a similar part 23 is formed in substantially the same manner as forming the butt part 11 except that the cylindrical bearing portions 24 are not curled to such 75 a great degree, so that the inner wall 23^a of the shank will terminate as at 25 to extend onto the bearings 24, and the outer wall 23^b at the bearings 24 as well as intermediate said bearings, is spaced from the pintle pin 26 in the formation of the hood 27, the free edge of which terminates at 28 in the stop shoulder similar to the shoulder 18.

In this construction, the bearings 24 encircle substantially two thirds of the circumference of the pin 26 and extend from the point 25 to the point 29, at which latter point, pressure may be applied to bring the bearings 24 in alignment with the free edge or shoulders 28 in the operation of compressing the bearings on the pin 26. With this construction, and by welding the parts 23^a and 23^b together as indicated at 30 as well as in other places, a strong and durable butt 80 will be provided, and one which will prevent 85 opening or spreading of the knuckle to a great degree.

In both forms of construction shown, it will be understood that the sheets or overlapping parts of the butt may be secured together in as many places as may be desired by welding, riveting or otherwise, and in the process of forming the butt parts 11 and 23 to produce a strong and durable hinge. If 90 desired, the knuckles or bearings 14 may be secured by welding to the adjacent part of the shank of the butt as at the point 14^a, note 95 Fig. 7 of the drawing to aid in securing the bearings against spreading when subjected to stress, but of course, this welding operation is not absolutely necessary.

100 It will also be understood that the separate butts of my improved hinge may be constructed with one or more knuckles or 105 pintle bearings on each butt, and the shank portions of the respective butts may be of any desired shape or contour, depending 110 upon the use of the hinge, it being understood that my invention is not limited to the specific use herein specified. It will also be apparent that my invention is not limited to any particular thickness of metal used in the construction of the hinge butts or the separate parts of the butts. Further, while I 115 have stated that the bearings 14 and 24 are compressed and secured to the pintle pins of the hinge, it will be understood that these bearings may be formed on a mandrel or other core, so that removable pivot pins may 120 125 130

be used in coupling the separate butts of the hinge together.

It will be understood that while I have shown certain details of construction for carrying my invention into effect, that I am not necessarily limited to these details, and various changes therein and modifications thereof may be made within the scope of the appended claims without departing 10 from the spirit of my invention or sacrificing its advantages.

Having fully described my invention, what I claim as new and desire to secure by Letters Patent, is:—

15 1. A hinge butt fashioned from a strip of sheet metal, the central portion of said strip being fashioned to form a plurality of spaced cylindrical bearings, and a hood portion extending from the material of said 20 bearings and overlying and partially encircling the wall of said bearings to form within said hood portion and between said bearings, recesses to receive the cylindrical bearings of the other butt of the hinge and the outer 25 wall of said hood portion being continuous with the outer exposed wall of said bearings.

2. A hinge butt fashioned from a strip of sheet metal, the central portion of said strip being fashioned to form a plurality of 30 spaced cylindrical bearings, and a hood portion extending from the material of said bearings and overlying and partially encircling the same to form within said hood portion and between said bearings, recesses 35 to receive the cylindrical bearings of the other butt of the hinge, and the outer wall of said hood portion being continuous with the outer exposed wall of said bearings, and that part of the hood portion encircling said 40 cylindrical bearings being of two thicknesses of sheet metal.

3. A hinge butt fashioned from a strip of sheet metal, the central portion of said strip being fashioned to form a plurality of 45 spaced cylindrical bearings, and a hood portion extending from the material of said bearings and overlying and partially encircling the same to form within said hood portion and between said bearings, recesses 50 to receive the cylindrical bearings of the other butt of the hinge, and the outer wall of said hood portion being continuous with the outer exposed wall of said bearings, that part of the hood portion encircling said 55 cylindrical bearings being of two thicknesses of sheet metal, and the hood portion intermediate said bearings consisting of a single sheet of metal, and the metal of said cylindrical bearings where it extends onto the 60 hood portion forming a stop shoulder in alinement with the free edge of said hood portion.

4. A hinge butt fashioned from a strip of sheet metal, the central portion of said strip 65 being fashioned to form a plurality of

spaced cylindrical bearings, and a hood portion extending from the material of said bearings and overlying and partially encircling the same to form within said hood portion and between said bearings, recesses to receive the cylindrical bearings of the other butt of the hinge, and the outer wall of said hood portion being continuous with the outer exposed wall of said bearings, that part of the hood portion encircling said cylindrical bearings being of two thicknesses of sheet metal, and the hood portion intermediate said bearings consisting of a single sheet of metal, the metal of said cylindrical bearings where it extends onto the hood portion forming a stop shoulder in alinement with the free edge of said hood portion, the shank of said butt being offset to provide an attaching plate portion, and said attaching plate portion being curved in a plane longitudinally of the butt.

5. A hinge butt of the class described fashioned from an elongated sheet of metal, the central portion of which is apertured at spaced intervals forming correspondingly spaced web members, and the side portions of said sheet being folded one upon another, and the central web portions curled to form of said webs, spaced cylindrical bearings, and a hood portion partially encircling said 90 bearings, said apertures forming within the hood portion and intermediate said bearings, spaced recesses to receive the bearings of the other butt of the hinge, and the outer exposed wall of the bearings of the first named butt being continuous with the outer wall of the hood portion where the free end of the hood portion joins said bearings.

6. In a covered joint hinge, a hinge butt the shank of which is composed of two ply thickness, a cylindrical bearing formed at one side of the shank and a hood partially encircling said bearing, the outer exposed wall of the bearing being continuous with the outer wall of the hood and the inner wall of the bearing being continuous with the inner wall of the hood forming a double wall thickness of the hood partially encircling said pintle bearing to reinforce and strengthen the same.

In testimony that I claim the foregoing as my invention I have signed my name this 15th day of Sept., 1927.

JOSEPH SOSS.
